UNITED STATES PATENT OFFICE.

ROY J. BLACKBURN, OF ST. LOUIS, MISSOURI, ASSIGNOR, OF ONE-HALF TO GEORGE G. PRENDERGAST, OF ST. LOUIS, MISSOURI.

PILE-PULLER.

1,111,784.

Specification of Letters Patent. Patented Sept. 29, 1914.

Application filed May 31, 1911. Serial No. 630,480.

To all whom it may concern:

Be it known that I, ROY J. BLACKBURN, a citizen of the United States, and resident of St. Louis, Missouri, have invented certain new and useful Improvements in Pile-Pullers, of which the following is a specification containing a full, clear, and exact description, reference being had to the accompanying drawings, forming a part hereof.

My invention relates to improvements in pile pullers, and the object of my invention is to construct a simple, durable and inexpensive machine for pulling piles, which machine is constructed of a minimum weight whereby it may be readily transported from place to place as required in its operation. And a further object of my invention is to construct a metallic head for the tripod of the machine, which head is of a minimum number of parts.

With the above purposes in view my invention consists in certain novel features of construction and arrangement of parts as will be hereinafter more fully set forth, pointed out in the claims and illustrated by the accompanying drawings, in which—

Figure 1 is a perspective of the complete pile puller; Fig. 2 is a plan of the tripod head showing a pulley supported therein; Fig. 3 is a transverse, sectional elevation taken on the line 3—3 of Fig. 2; Fig. 4 is a perspective of the V-shaped frame member for the support of the head; Fig. 5 is a perspective of one of the side frame members of the head; and Fig. 6 is a perspective of the top plate of the head.

Referring by numerals to the accompanying drawings: 1 and 2 designate the channel bar frame members for the sides of the tripod head. These channel bars are bent to form a substantially Y-shaped frame.

3 designates a V-shaped frame member which is disposed at the open or top end of the Y-shaped frame consisting of the channel bars 1 and 2.

4 designates a plate which connects the frame members 1, 2 and 3 and is secured to the channel bar frame members preferably by riveting to the upper flanges of the members. The plate 4, at its approximate center, is provided with an aperture 5.

6—6 designate angle plates which are secured to the plate 4 on either side of the aperture 5.

7—7 designate plates which are secured to the angle plates 6 with portions thereof projecting downwardly through the aperture 5 and projecting above the angle plates 6. Arranged adjacent the upper margin of each of the plates 7 there are journal bearings supporting a shaft 8 upon which is carried the pulley 9. At the lower end of the plates 7, beneath the plate 4, there is a bolt 10 upon which there is secured a link 11 arranged for the support of the yoke 12 in which is carried a block 13.

14 designates a link which is arranged for connection with a pile 15, the link 14 being connected with the yoke 16 in which yoke is carried the block 17, the two blocks 13 and 17 being connected with a tackle rope 18, the end 19 of which rope leads to a suitable hoisting mechanism not shown.

The pulley 9 is embraced by a rope 20 which leads to the hoisting mechanism referred to and is used principally for the convenient handling of the tripod, the rope 18 and the tackle blocks referred to being employed for the pulling of the piles.

The vertical portions of the channel bars 1 and 2 are perforated adjacent their ends and the vertical portions of the V-shaped member 3 are each perforated. In the perforations are supported the bolts 21 upon which are pivotally supported the legs 22.

In the operation of the machine, assuming the ropes 19 and 20 to be connected with the arm of the hoisting mechanism, the tripod is swung to position on the rope 20 and the legs 22 placed in position over the pile to be pulled. The link 14 is then connected with the pile and the end 19 of the rope is drawn by the hoisting mechanism and the pile is started or loosened from the earth through the medium of the tripod and the tackle. After the pile has been sufficiently loosened by the tackle the completion of the drawing of the pile is accomplished by the elevating of the entire machine through the medium of the rope 20.

I claim:

In a pile puller, a tripod, a tackle supported by and overhead the tripod and ar-

ranged to be connected with a hoisting machine, and a tackle suspended from the tripod and arranged to be connected with a pile and said hoisting machine, whereby a
5 pile may be first acted upon by said suspended tackle and then acted upon by said overhead tackle.

In testimony whereof, I have signed my name to this specification, in presence of two subscribing witnesses.

ROY J. BLACKBURN.

Witnesses:

E. L. WALLACE,
N. G. BUTLER.
